UNITED STATES PATENT OFFICE.

HAROLD CURTICE SANDERS, OF NEWPORT, WALES.

ELECTRICAL APPARATUS FOR HEATING LIQUIDS.

1,396,597.

Specification of Letters Patent.

Patented Nov. 8, 1921.

Application filed July 27, 1920. Serial No. 399,367.

To all whom it may concern:

Be it known that I, HAROLD CURTICE SANDERS, a subject of the King of England, residing at 34 Bridge street, Newport, in the county of Monmouth, Wales, whose post-office address is 34 Bridge street, Newport, in the county of Monmouth, Wales, have invented certain new and useful Improvements in Electrical Apparatus for Heating Liquids, of which the following is a specification.

This invention relates to electric heating apparatus of the kind in which liquids are heated by the transmission of the heat generated by an electric current passed through a bare resistance wire over and around which the liquid flows.

The present invention refers to an improved construction of such electric liquid heating apparatus in which the general arrangement of the apparatus is such as to provide that the heating coil is horizontally disposed and connected from above by metallic plates in a container or body formed as an oblong basin comprising a trough, a reservoir, an inlet pipe discharging at the upper part of said reservoir, liquid outlets from said reservoir to the lower part of the trough and outlets from the trough around the outer sides and front of the reservoir and at a lower level than the discharge end of the inlet pipe. Furthermore, the apparatus is provided with means whereby the inflowing liquid will complete the electric circuit through the coil, the circuit being broken when the liquid supply is discontinued or reduced to a flow insufficient in quantity to absorb the heat units given off by the element.

40 In the accompanying drawings,

Figure 1 is a half-sectional elevation of my improved electric heater;

Fig. 2 is a half-sectional plan of same; and

45 Fig. 3 is a vertical section taken on the line 3-3 in Fig. 1.

Fig. 4 is a view similar to Fig. 3 showing the means for automatically closing the electric circuit through the heating coil.

50 Fig. 5 is a plan of a modification of the heater shown in Figs. 1 to 3.

The same letters of reference where they

occur are used to denote the same or corresponding parts in all the figures of the drawings.

55 Referring first to Figs. 1 to 3:—

The heater comprises two main parts a body A preferably molded in one piece from porcelain or the like, and a cover plate B secured to the body by means of screw studs 60 C and nuts D, the studs C being molded in, screwed into, or otherwise affixed to the body.

The body A is made in the form of an oblong basin and comprises or contains a 65 trough or channel a, a reservoir a¹ and liquid outlet passages a² around the outer side and front surfaces of the reservoir and leading to a discharge spout at a³.

Passing through the back of the body are 70 two screw-studs a⁴ connected outside the vessel by leads a⁵ to a suitable source of electricity and connected inside the vessel by metallic plates a⁶ with the heating coil E resting upon or near to the bottom of the 75 trough or channel a.

The rear of the discharge spout a³ is covered by a perforated wire plate F which extends across the outlet from the passages a² and is connected to earth through a metallic plate F¹ and bolt G, passing through an aperture A¹ in the body A, and thence to any suitable place for earthing.

The body A is provided with a liquid inlet pipe H which extends upward through 85 and discharges into the reservoir a¹ at or near to the upper part thereof. The reservoir is connected with the trough a by means of apertures a⁷ in the lower part of said reservoir at or near the longitudinal center of 90 the trough, and the trough or channel a discharges at its ends into the outlet passages a² which are located at a level below that of the discharge from the inlet H to the reservoir. Consequently there is always a water 95 trap in the vessel of the height of that from the outlet passages a²; below which trap-level the heating element E is located and is therefore always immersed after liquid is once admitted to the apparatus.

100 The action of this part of the apparatus is as follows:—

The liquid to be heated enters the vessel through the inlet H and discharges at the

upper end thereof into the reservoir a^1 ; thence it passes through the central apertures a^2 into the lower part of the trough a containing the heating element E where it 65 diverges and flows to the ends of the trough and rises and overflows along the outlet passages a^2 which converge to the discharge spout a^3 , from whence the liquid flows after having discharged, through the earthed plate F , any electricity it may have taken up in its passage around the element E . It will be seen that the flow of the liquid is that best adapted to effect a rapid heating, 70 namely it enters at the lower part of the 10 apparatus and leaves at the upper part, passing in its passage completely along and over the heating element, *i. e.*, from the center to both of the ends of said element.

It will be observed that, with the apparatus 20 as hereinbefore described the liquid supply and the electric current require to be separately operated, but to provide for the simultaneous action of both I have devised means whereby the inflowing water completes the electric circuit through the heating element.

This arrangement is shown in Fig. 4 30 wherein the liquid inlet H is fitted with a piston J carrying on its upper end a tray having a centrally disposed pipe K^1 communicating with a central channel J^1 passing through the piston J , and discharging into the tray at the upper part thereof, so that when liquid is once admitted thereto the tray will be always full.

Above the tray are the contacts of a switch, or a series of contact plates L insulated by air gaps as shown, and the rising tray K will, by immersion of the contacts or 40 plates in the liquid, close the switch through the liquid and afterward will short-circuit the plates by means of a metallic conductor K^2 on the bottom of the tray.

To enable the liquid to pass to the reservoir a^1 the lower part of the piston J is cut away longitudinally to provide longitudinal channels or ways J^2 through which the liquid will discharge over the top of the inlet pipe H into the reservoir a^1 when the 45 piston has risen sufficiently. The further rise of the piston will cause the tray K to complete the circuit through the contact plates L .

In the modification shown in Fig. 5 the 55 heating apparatus is adapted to the three-wire electricity supply system and liquid outlet passages not being necessary are dispensed with.

In this form two elements $E E^1$ are used, 60 both connected to a middle wire terminal E^2 , and the trough a is located between the reservoir a^1 and the spout a^3 , the liquid rising in the trough and discharging direct therefrom through the gauze plate F to the

spout a^3 . As before the discharge at a^3 is 65 below the level of the liquid inlet at H , and the heating elements $E E^1$ are located below both levels.

The circuit completing device shown in Fig. 4 can be applied to this form of my invention if so desired.

The principal advantages of my present construction are that the reservoir, for containing the water and the element immersed therein, is of compact form, and that the apparatus comprises but few parts which can be readily dismantled when repairs or renewals are required.

What is claimed as new is:

1. An electric liquid heater comprising in 80 combination a container formed as an oblong basin, a trough in said container, a heating element arranged horizontally in said trough, a reservoir in said container bounded by the wall of the trough and the body 85 of the container, a liquid inlet passing through the bottom of the container into the reservoir and discharging at the upper part of said reservoir, apertures in the lower part of the wall separating the trough and reservoir, and a liquid discharge outlet connected to said trough at a lower level than the discharge end of the liquid inlet within the reservoir.

2. An electric liquid heater comprising in 95 combination a container formed as an oblong basin, a trough in said container, a heating element arranged horizontally in said trough, a reservoir in said container bounded by the wall of the trough and the body 100 of the container, a liquid inlet passing through the bottom of the container into the reservoir and discharging at the upper part of said reservoir, apertures in the lower part of the wall separating the trough and reservoir, liquid outlet passages or channels formed in the wall of the reservoir and extending from the trough around the outer sides and front of the reservoir and at a 105 lower level than the discharge end of the liquid inlet within the reservoir, and a liquid discharge outlet at the termination of the said passages or channels.

3. An electric liquid heater comprising in 115 combination a container formed as an oblong basin, a trough in said container, a heating element comprising a bare resistance wire arranged horizontally in said trough so as to be at all times entirely immersed in the liquid to be heated, metallic plates connected 120 to said heating element, screw-studs passing through the body of the container to which studs said plates are connected, a reservoir in said container bounded by the wall of the trough and the body of the container, a liquid inlet passing through the bottom of the container into the reservoir and discharging at the upper part of said reservoir, aper-

tures in the lower part of the wall separating the trough and reservoir, and a liquid discharge outlet connected to said trough at a lower level than the discharge end of the liquid inlet within the reservoir.

4. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of the container to which stud said plates are connected, a reservoir in said container bounded by the wall of the trough and the body of the container, a liquid inlet passing through the bottom of the container into the reservoir and discharging at the upper part of said reservoir, apertures in the lower part of the wall separating the trough and reservoir, liquid outlet passages or channels formed in the wall of the reservoir and extending from the trough around the outer sides and front of the reservoir and at a lower level than the discharge end of the liquid inlet within the reservoir, and a liquid discharge outlet at the termination of said passages or channels.

5. An electric liquid heater comprising in combination a container formed as an oblong basin, a trough in said container, a heating element arranged horizontally in said trough, a reservoir in said container bounded by the wall of the trough and the body of the container, a liquid inlet passing through the bottom of the container into the reservoir and discharging at the upper part of said reservoir, means connected to the discharge end of the liquid inlet to cause the electrical circuit through the heating element to be closed primarily through the liquid, apertures in the lower part of the wall separating the trough and reservoir, and a liquid discharge outlet connected to said trough at a lower level than the discharge end of the liquid inlet within the reservoir.

6. An electric liquid heater comprising in combination a container formed as an oblong basin, a trough in said container, a heating element arranged horizontally in said trough, a reservoir in said container bounded by the wall of the trough and the body of the container, a liquid inlet passing through the bottom of the container into the reservoir and discharging at the upper part of said reservoir, means connected to the discharge end of the liquid inlet to cause the electrical circuit through the heating element to be closed primarily through the liquid, apertures in the lower part of the wall separating the trough and reservoir, liquid outlet passages or channels

formed in the wall of the reservoir and extending from the trough around the outer sides and front of the reservoir and at a lower level than the discharge end of the liquid inlet within the reservoir, and a liquid discharge outlet at the termination of the said passages or channels.

7. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of the container to which studs said plate are connected, a reservoir in said container bounded by the wall of the trough and the body of the container, a liquid inlet passing through the bottom of the container into the reservoir and discharging at the upper part of said reservoir, means connected to the discharge end of the liquid inlet to cause the electrical circuit through the heating element to be closed primarily through the liquid, apertures in the lower part of the wall separating the trough and reservoir, and a liquid discharge outlet connected to said trough at a lower level than the discharge end of the liquid inlet within the reservoir.

8. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of the container to which studs said plates are connected, a reservoir in said container bounded by the wall of the trough and the body of the container, a liquid inlet passing through the bottom of the container into the reservoir and discharging at the upper part of said reservoir, means connected to the discharge end of the liquid inlet to cause the electrical circuit through the heating element to be closed primarily through the liquid, apertures in the lower part of the wall separating the trough and reservoir, liquid outlet passages or channels formed in the wall of the reservoir and extending from the trough around the outer sides and front of the reservoir and at a lower level than the discharge end of the liquid inlet within the reservoir, and a liquid discharge outlet at the termination of said passages or channels.

9. An electric liquid heater comprising in combination a container formed as an oblong basin, a trough in said container, a heating

element arranged horizontally in said trough, a reservoir in said container bounded by the wall of the trough and the body of the container, a liquid inlet passing through 5 the bottom of the container into the reservoir and discharging at the upper part of said reservoir, a piston fitted in the discharge end of the liquid inlet, a central channel through said piston, a tray secured to said piston, a central pipe in said tray communicating with the channel in the piston, metallic contact plates in said tray, a series of contact plates located above said tray and in the electrical circuit with which 10 contact plates the metallic plates in the tray make contact when in the raised position, apertures in the lower part of the wall separating the trough and reservoir, and a liquid discharge outlet connected to said 15 trough at a lower level than the discharge end of the liquid inlet within the reservoir.

10. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of 20 the container to which studs said plates are connected, a reservoir in said container bounded by the wall of the trough and the body of the container, a liquid inlet passing through the bottom of the container into 25 the reservoir and discharging at the upper part of said reservoir, a piston fitted in the discharge end of the liquid inlet, a central channel through said piston, a tray secured to said piston, a central pipe in said tray 30 communicating with the channel in the piston, metallic contact plates in said tray, a series of contact plates located above said tray and in the electrical circuit with which 35 contact plates the metallic plates in the tray make contact when in the raised position, apertures in the lower part of the wall separating the trough and reservoir, liquid 40 outlet passages or channels formed in the wall of the reservoir and extending from the trough around the outer sides and front of the reservoir and at a lower level than the discharge end of the liquid inlet within the reservoir, and a liquid discharge outlet at the termination of the said passages or 45 channels.

11. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of 50 the container to which studs said plates are connected, a reservoir in said container bounded by the wall of the trough and the body of the container, a liquid inlet passing through the bottom of the container into 55 the reservoir and discharging at the upper part of said reservoir, a piston fitted in the discharge end of the liquid inlet, a central channel through said piston, a tray secured to said piston, a central pipe in said tray 60 communicating with the channel in the piston, metallic contact plates in said tray, a series of contact plates located above said tray and in the electrical circuit with which contact plates the metallic plates in the tray make contact when in the raised position, apertures in the lower part of the wall separating the trough and reservoir, liquid outlet passages or channels formed in the wall of the reservoir and extending from the trough around the outer sides and front of the reservoir and at a lower level than the discharge end of the liquid inlet within the reservoir, and a liquid discharge outlet at the termination of the said passages or 65 channels.

12. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of 70 the container to which studs said plates are connected, a reservoir in said container bounded by the wall of the trough and the body of the container, a liquid inlet passing through the bottom of the container into 75 the reservoir and discharging at the upper part of said reservoir, a piston fitted in the discharge end of the liquid inlet, a central channel through said piston, a tray secured to said piston, a central pipe in said tray 80 communicating with the channel in the piston, metallic contact plates in said tray, a series of contact plates located above said tray and in the electrical circuit with which contact plates the metallic plates in the tray make contact when in the raised position, apertures in the lower part of the wall separating the trough and reservoir, and a liquid discharge outlet connected to said trough at a lower level than the discharge end of the liquid inlet within the reservoir.

13. An electric liquid heater comprising in combination a container formed as an oblong basin, a trough in said container, a heating element comprising a bare resistance wire arranged horizontally in said trough so as to be at all times entirely immersed in the liquid to be heated, metallic plates connected to said heating element, screw-studs passing through the body of 85 the container to which studs said plates are connected, a reservoir in said container bounded by the wall of the trough and the body of the container, a liquid inlet passing through the bottom of the container into 90 the reservoir and discharging at the upper part of said reservoir, a piston fitted in the discharge end of the liquid inlet, a central channel through said piston, a tray secured to said piston, a central pipe in said tray 95 communicating with the channel in the piston, metallic contact plates in said tray, a series of contact plates located above said tray and in the electrical circuit with which contact plates the metallic plates in the tray make contact when in the raised position, apertures in the lower part of the wall separating the trough and reservoir, liquid outlet passages or channels formed in the wall of the reservoir and extending from the trough around the outer sides and front of the reservoir and at a lower level than the discharge end of the liquid inlet within the reservoir, and a liquid discharge outlet at the termination of the said passages or 100 channels.

14. A liquid heater comprising a container having an inlet and an outlet, a chamber open to the inlet and having its bottom wall extending from a level below the inlet to a level above the outlet, and an electric 105

heating element arranged on the bottom of said chamber.

15. An electric liquid heater comprising a container formed to present a reservoir having an inlet, a heating chamber open to the reservoir and having its bottom wall curving upwardly from an intermediate point, and an outlet channel communicating with the higher points of the chamber and

leading to an outlet, and an electric heating element on the bottom of said chamber.

In testimony whereof I have hereunto set my hand in presence of two subscribing witnesses this ninth day of July, 1920.
